DESIGN FOR A LAMP SHADE

Eugene Schwarz, Alexandria, Ind., assignor to
The Mantle Lamp Company of America, Chi-
cago, Ill., a corporation of Illinois

Application August 6, 1934, Serial No. 52,838

Term of patent 3½ years

To all whom it may concern:

Be it known that I, EUGENE SCHWARZ, a citizen of the United States of America, residing at Alexandria, in the county of Madison and State of Indiana, have invented a new, original, and ornamental Design for Lamp Shades, of which the following is a specification, reference being had to the accompanying drawing, forming a part thereof:

Fig. 1 is a view in elevation of a lamp shade, showing my new design, and

Fig. 2 is a view in elevation of one of the sections of said shade.

The lamp shade is composed of a plurality of individually-curved and tapered sections which give the shade a substantially frusto-conical contour and a corrugated appearance. The surface ornamentation, shown in Fig. 2, is repeated on each of the sections throughout the circumference of the shade.

I claim:

The ornamental design for a lamp shade, substantially as shown and described.

In testimony whereof I affix my signature.

EUGENE SCHWARZ.
